(57) **CLAIM**

The ornamental design for a display screen or portion thereof with icon, as shown and described.

DESCRIPTION

FIG. 1 is a front view of a display screen or portion thereof with icon showing our new design; and, FIG. 2 is a second embodiment thereof.

The broken lines around the Figures showing a display screen or portion thereof form no part of the claimed design. The broken lines within the icon in FIG. 2 show portions that form no part of the claimed design.
